Primary Examiner — Llorellys Martinez*(74) Attorney, Agent, or Firm* — Honigman LLP(57) **CLAIM**

The ornamental design for a below top of wall ventilation screed device, as shown and described.

DESCRIPTION

FIG. 1 is a top, front perspective view of a below top of wall ventilation screed device showing our new design;

FIG. 2 is a front view of the below top of wall ventilation screed device;

FIG. 3 is a back view of the below top of wall ventilation screed device;

FIG. 4 is a left side view of the below top of wall ventilation screed device;

FIG. 5 is a right side view of the below top of wall ventilation screed device;

FIG. 6 is a top side view of the below top of wall ventilation screed device;

FIG. 7 is a bottom side view of the below top of wall ventilation screed device; and,

FIG. 8 is a top, back perspective view of the below top of wall ventilation screed device.
